EZRA W. HAVEN, OF BRANDON, VERMONT.

Design No. 4,199, dated July 5, 1870.

DESIGN FOR A PICTURE-FRAME.

The Schedule referred to in these Letters Patent and making part of the same.

I, EZRA W. HAVEN, of Brandon, in the county of Rutland and State of Vermont, have invented and produced a new and original Design for a Picture-Frame, of which the following is a specification.

The nature of my design is represented in the accompanying drawings, to which reference is made.

It consists of a frame of cast-iron, having the several spaces a a a a for portraits, and a larger space, b, for a symbol, coat of arms, an emblem, or other device.

It is intended for lodges, associations, or families.
I claim—
The design for a picture-frame, substantially as above set forth.

E. W. HAVEN.
